UNITED STATES PATENT OFFICE.

FRED D. RICKERT, OF READING, PENNSYLVANIA.

DESIGN FOR A SOCK.

Application filed October 24, 1922. Serial No. 4,072. Term of patent 7 years.

To all whom it may concern:

Be it known that I, FRED D. RICKERT, a citizen of the United States, residing at Reading, in the county of Berks and State of Pennsylvania, have invented a new, original, and ornamental Design for a Sock, of which the following is a specification, reference being had to the accompanying drawing, forming part thereof.

The figure is an elevation of a sock, showing my design.

I claim:

The ornamental design for a sock, as shown.

FRED D. RICKERT.
